UNITED STATES PATENT OFFICE

FRED W. ZINK, OF DETROIT, MICHIGAN, ASSIGNOR TO KALES STAMPING COMPANY,
OF DETROIT, MICHIGAN, A CORPORATION

LEVER

Application filed July 14, 1924. Serial No. 725,957.

The invention relates to levers especially adapted to be made by stamping or pressing the parts from sheet metal. It is an object of my invention to construct a lever of the character referred to, which shall be simple in construction. A further object of my invention is to provide a lever permitting manufacture at a low cost and to provide a construction of great strength. It is a further object of my invention to provide a lever adapted for use with automobile control rods, or other machines.

With these and other objects in view, the invention resides in the novel features of construction and combinations and arrangements of parts as more fully hereinafter described and claimed.

In the drawings:

Figure 1 is a perspective view of my lever shown connected with a rod;

Figure 2 is a section on the line 2—2 of Figure 1;

Figure 3 is a section on the line 3—3 of Figure 2;

Figure 4 is a perspective view of one of the connector caps, and

Figure 5 is an elevation of one of the body members.

Referring to the drawings, the lever comprises a pair of similar body portions or members 10 and 10'. The body members are formed by a pressing or stamping operation and each is provided at one end with a perforation 11 for receiving a member (not shown) operably connected with the lever. At the other end the body members 10 and 10' are separated as shown and are preferably formed with enlarged face portions 12 perforated at 13 to receive the controlling rod 14. Extending longitudinally along the body members 10 are the slots 15. These slots connect with perforations 13 and preferably extend beyond the centers of the body members 10 to afford a certain amount of silence in connection with the clamping means described hereinafter.

The provision of the slots 15 also considerably lessens the weight of the lever. Adjacent the rod 14 each body member 10 is provided with upper and lower recessed portions

16 and 17 forming shoulders 18 and 19 respectively. The portions of the body members 10 between the ends having the perforations 11 and the shoulders 18 and 19 are preferably adapted to lie in face contact as shown. Between the shoulder portions 18 and 19 and the offset face portions 12, the body members are formed with parts 20 and 21 preferably curved outwardly as shown, to accommodate the clamping bolt 22 which extends perpendicularly with respect to the body members 10 and lies substantially in the plane of contact of the body members. Connector caps 23, and 24 are mounted in the recessed portions 16 and 17 respectively. Each cap is preferably formed of a stamping and is provided with a tongue 25 preferably the width of the space separating the face portions 12. The caps also have the flanged portions 26 preferably curved to conform with the parts 20 and 21. Flattened portions 27 are adapted to engage the shoulders 18 and 19. Perforation 28 accommodates passage of the clamping bolt 22. The clamping bolt is provided at one end with a head 29 bearing upon cap 24 and at the other end is adapted to receive a lock nut 30 bearing upon the cap 23.

In assembling my lever the body members are placed in position with the recesses 13 engaging the rod 14 and the other ends lying in face contact. The connector caps 23 and 24 are then placed in the recesses 16 and 17 respectively with the flanged portions 26 and 27 engaging the faces of the curved parts 20 and 21 and the flattened portions 27 engaging the shoulders 18 and 19. The tongues 25 are extended between the face portions 12 of the body members 10 adjacent the rod 14 as shown in Figure 2. The clamping bolt 22 is then positioned as shown and the lock nut 30 engaged therewith. The dimensions of the lock nut are preferably such that its corners engage the shoulder 20 or the edges of the face portions 12 so that by rotating the bolt by the head 29 the nut is prevented from rotating and the parts are firmly clamped in position relative to the central rod 14. The slot 15 will afford sufficient resilience so that in clamping the body members 10 on the con-

trol rod the body members may be slightly sprung to place the parts under a tension. In this manner, the lever is securely connected to the control rod. The flanges 26 of the caps and the flat portions 27 will prevent rotation or displacement of the caps as will be readily understood.

It will thus be seen that I have provided a lever having body members 10 similarly formed preferably of a sheet metal stamping and capable of being produced at a single operation. The caps 24 are likewise preferably sheet metal stampings.

While it is believed that from the foregoing description, the nature and advantages of my invention will be readily understood, I desire to have it understood that I do not limit myself to what is herein shown and described and that such changes may be resorted to when desired as fall within the scope of the claims.

What I claim as my invention is:

1. A lever comprising a pair of longitudinally extending body members spaced apart at one end, said members having recesses in their upper and lower edges, means associated with the corresponding recesses of each member for holding the members in position, and a clamping member having portions bearing upon said holding means.

2. A lever comprising a pair of body members having aligned longitudinally extending slots, and recesses at corresponding points along the edges of the body members, cap members seated in said recesses, and means urging the cap members toward each other for clamping the lever body members in operative position.

3. A lever comprising a pair of body members having face contact at one end and separated at the other end to provide face portions connected to the first said end through curved portions, connector caps curved to correspond with the said curved portions, and bearing upon the upper and lower edges of the body members respectively, and clamping means extending between the body members and bearing upon said connector caps.

4. A lever comprising a pair of body members having face contact at one end and separated at the other end to provide face portions connected to the first said end through curved portions, connector caps curved to correspond with the said curved portions, and bearing upon the upper and lower edges of the body members respectively, and clamping means extending between the body members and bearing upon said connector caps, each retaining cap having a tongue positioned between the said separated face portions of the body members.

5. A lever comprising a pair of body members having face contact at one end and separated at the other end to provide face portions connected to the first said end through

curved portions, connector caps curved to correspond with the said curved portions, and bearing upon the upper and lower edges of the body members respectively, and clamping means extending between the body members and bearing upon said connector caps, each retaining cap having a tongue positioned between the said separated face portions of the body members, and a flattened portion bearing against the body members.

6. A lever of the class described comprising two separable similar body portions arranged back to back throughout the major portion of their length and provided at one end with diverging face portions having aligned openings for receiving a rod, said body portions having registering longitudinally extending slots opening into said openings, and means for holding said body portions in assembled position including clips having portions embracing longitudinal edges of said body portions and having portions extending between the diverging face portions aforesaid, a bolt extending through said clips, and a nut carried by said bolt.

7. A lever of the class described comprising two separable similarly formed members in substantially parallel planes having arched portions, and portions diverging from said arched portions and provided with aligned openings for receiving a rod, and a connection between said members including a bolt received in said arched portions, and clips on said bolt having portions embracing portions of said members and having other portions extending between and constituting spacers for the diverging portions aforesaid.

8. A lever of the class described comprising two separable similarly formed members in substantially parallel planes and having diverging portions provided with aligned openings for receiving a rod, and a connection between said members including a bolt associated with said member, and clips on said bolt having portions embracing portions of said members and having other portions extending between and constituting spacers for the diverging portions aforesaid.

9. A lever of the class described comprising two separable similar body members in parallel planes having diverging portions provided with aligned openings for receiving a rod, a bolt extending between said body portions, a nut carried by said bolt, and clips on said bolt between the nut and the head of the bolt and having portions embracing portions of said body portions and having other portions extending between and constituting spacers for the diverging portions aforesaid of said body portions.

In testimony whereof I affix my signature.

FRED W. ZINK.
